Primary Examiner — Deanna L. Pratt*Assistant Examiner* — Lilyana Bekic(74) *Attorney, Agent, or Firm* — Kenyon & Kenyon LLP(57) **CLAIM**

The ornamental design for a member of an inhaler device, as shown and described.

DESCRIPTIONFIG. 1 is a top and left side perspective view of a member of an inhaler device showing my new design;
FIG. 2 is a rear elevational view thereof;
FIG. 3 is a front elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a bottom, left side and rear perspective view thereof. The broken lines in the drawings illustrate portions of the member of an inhaler device which form no part of the claimed design.**1 Claim, 4 Drawing Sheets****FIG. 1**
